5 Claims. (Cl. 131—245)

ABSTRACT OF THE DISCLOSURE

A device for cleaning the mouthpiece of pipes, cigarette holders, cigar holders and the like having a plurality of angularly disposed resiliently deformable tines covered with flocking which is pulled through the mouthpiece for cleaning the same.

This invention relates generally, as indicated, to a pipe cleaner and, more particularly, to a novel device for effectively cleaning the entire wall area of the air passage through a pipe mouthpiece or the like.

There are a great many different types of pipe cleaners presently on the market, some of which are more effective in cleaning pipe stems or cigarette and cigar holders than others. However, none of them consists of a plurality of angularly disposed resiliently deformable tines with flocking thereon which are pulled through the holder for removing tobacco tars or other dirt particles from the difficult to reach areas along the side walls of the oval shape entrance in the holder leading to the bore therethrough.

It is accordingly a principal object of this invention to provide a novel device for effectively removing dirt accumulations from the mouthpiece of pipes and cigarette and cigar holders even along the remote side walls of the oval shaped entrance to the air passages therethrough.

Another object is to provide such a cleaning device with a plurality of angularly disposed flexible cleaning tines which resiliently engage the side walls of the mouthpiece bore during movement of such cleaning device therethrough to facilitate removal of encrusted dirt and tobacco tars therefrom which have been allowed to accumulate for a day or two.

Another object is to provide such a device in which the tines are fanned out all in the same plane to permit engagement thereby of the remote side walls of the oval shape entrance in the mouthpiece.

Still another object is to provide such a device with a long flexible shaft which may be inserted through the mouthpiece opening and grasped for pulling of the tines therethrough.

Other objects and advantages of the present invention will become apparent as the following description proceeds.

To the accomplishment of the foregoing and related ends, the invention, then, comprises the features herein-after fully described and particularly pointed out in the claims, the following description and the annexed drawing setting forth in detail certain illustrative embodiments of the invention, these being indicative, however, of but several of the various ways in which the principles of the invention may be employed.

In such annexed drawing:

FIG. 1 is a top plan view of a preferred form of cleaning device in accordance with this invention shown with its shaft extending through the mouthpiece of a pipe or the like to be cleaned thereby;

FIG. 2 is an enlarged isometric view of the cleaning detail of FIG. 1; and

FIGS. 3 and 4 are fragmentary isometric views similar to FIG. 2, but of two other embodiments of cleaning devices in accordance with the present invention.

2

Turning now to the details of the various forms of pipe cleaners illustrated by way of example in the drawing, and first of all to the FIGS. 1 and 2 form, such cleaning device is generally indicated by the numeral 1 and comprises a substantially straight shaft 2 having a plurality of flexible tines 3 secured to one end thereof. The shaft 2 is preferably of a diameter between two to three times smaller than the minimum dimension of the passage 4 through a mouthpiece 5 of a pipe stem 6 or cigarette or cigar holder, as the case may be, and is of a length such that its leading end may be inserted completely through the mouthpiece 5 before the tines 3 enter such mouthpiece. Moreover, the leading end is desirably bent back on itself as shown in FIG. 2 or is in the shape of a P or arrowhead such as illustrated in the FIG. 3 embodiment not only to guide the shaft 2 through the mouthpiece 5, but also to provide a blunt end which will not stab or scratch the person using the device and can easily be grasped as between the thumb and the first finger for pulling the tines 3 through the opening 4.

In the cleaning device 1 illustrated, the tines 3 consist of a pair of relatively short pieces of wire 7, each about 2½ inches long, covered with a suitable absorbent fibrous material 8 such as woven fabric or white flock with a non-toxic acetate base sprayed on the wires before flocking, and bent at an angle of about 30° at the middle of their lengths into a V shape to form each wire into two such tines. The wires 7 are next attached to the trailing end 9 of the flexible shaft 2 as by heating such trailing end to soften it so that it may be flattened by pounding, flattening such end, and then bending the flattened end around the middle of the wires to clamp them in place with the tines 3 disposed in the same plane but approximately ½ inch apart. Alternatively, the tines 3 may be spot-welded to the trailing end of the shaft 2 as in the FIG. 3 embodiment, or they may be formed by twisting together a plurality of wire strands 10 with the ends 11 spread apart in pan shape as in the FIG. 4 embodiment and flocking such ends 11 in the manner described above.

As an example, the shaft 2 may be No. 20, .0320 inch diameter non-magnetic soft Monel metal wire 5½ inches in length, and the wires 7 may be No. 28, .0126 inch diameter or No. 29, .0113 inch diameter Monel metal wire 2½ inches long with .060 inch diameter flocking thereon. However, it should be understood that other flexible materials could be used for the wire, such as stainless steel or certain plastics such as nylon, for example. The only requirement for the shaft 2 is that it be sufficiently rigid that it does not buckle when inserted through the mouthpiece opening 4 or break during pulling of the tines 3 through such opening by the shaft. The tines 3, on the other hand, must be of spring material which may be flexed, in a manner fully explained hereinbelow.

In use, the cleaning device 1 is oriented so that the plane of the tines 3 is parallel to the widest dimension of the oval shape entrance 12 of the mouthpiece opening 4. Then the leading end 6 of the shaft 2 is inserted into the opening 4 and pushed therethrough until it projects beyond the other end of such opening, after which the rebent end 6 is gripped for pulling of the flexible tines 3 through such opening. As evident, as the tines 3 are drawn through the opening 4, they are flexed inwardly by the walls 13 of the opening even at its widest dimension which is the width of the oval shape entrance 12. This inward flexing causes the tines 3 to yieldably engage the walls 13, thus providing a strong wiping action for removing even encrusted dirt particles and tobacco tars therefrom. The walls defining the narrow dimension of the entrance 12 are also engaged by the tines 3, but not yieldably engaged thereby. Of course, the maximum di-

mension of the tines 3 collectively when squeezed together must be small enough to pass through the smallest dimension of the opening 4.

It can now be seen that the cleaning device of the present invention is of a unique construction which is capable of removing dirt particles and the like from the remote surfaces of the walls of a mouthpiece opening especially at the widest dimension of the oval shape entrance which was heretofore generally not possible. Moreover, even where the dirt particles have hardened somewhat for failure regularly to clean the mouthpiece, such dirt particles can be removed by the cleaning device of the present invention due to the resilient wiping force created by the flexible tines.

Other modes of applying the principles of the invention may be employed, change being made as regards the details described, provided the features stated in any of the following claims or the equivalent of such be employed.

I therefore, particularly point out and distinctly claim as my invention:

1. A device for cleaning the opening through a mouthpiece for pipes, cigarette holders, cigar holders, and the like comprising a plurality of angularly disposed resiliently deformable tines all in the same plane and spread apart in fan shape, said tines being covered with a fibrous material, and shaft means to which said tines are attached for pulling said tines in a forward direction through the opening of a mouthpiece, said tines extending rearwardly from one end of said shaft means and being adapted to be resiliently biased against the wall of such opening during passage therethrough for removing tobacco tars and dirt particles therefrom, said shaft means comprising a plurality of wire strands twisted together, the wire strands at said one end of said shaft means being spread apart in fan shape as aforesaid to provide said tines.

2. A device for cleaning the opening through a mouthpiece for pipes, cigarette holders, cigar holders, and the like comprising a plurality of angularly disposed resiliently deformable tines all in the same plane and spread apart in fan shape, said tines being covered with a fibrous material, shaft means to which said tines are attached for pulling said tines in a forward direction through the opening of a mouthpiece, said tines extending rearwardly from one end of said shaft means and being adapted to be resiliently biased against the wall of such opening during passage therethrough for removing tobacco tars and dirt particles therefrom, said tines consisting of a plurality of wires each bent at the middle of its length into a V-shape to provide two of said tines, and means for rigidly attaching said wires to said one end of said shaft

means at their middle, said means for rigidly attaching said wires to said one end of said shaft means comprising welded connections between said shaft means and said wires at their middle.

5 3. A device for cleaning the opening through a mouthpiece for pipes, cigarette holders, cigar holders, and the like comprising a plurality of angularly disposed resiliently deformable tines all in the same plane and spread apart in fan shape, said tines being covered with a fibrous material, shaft means to which said tines are attached for pulling said tines in a forward direction through the opening of a mouthpiece, said tines extending rearwardly from one end of said shaft means and being adapted to be resiliently biased against the wall of such opening during passage therethrough for removing tobacco tars and dirt particles therefrom, said tines consisting of a plurality of wires each bent at the middle of its length into a V-shape to provide two of said tines, and means for rigidly attaching said wires to said one end of said shaft means at their middle, there being two of said wires bent at their middle into V-shape to provide four of said tines, said wires being bent at approximately the same angle and the middle of said wires being attached to said one end of said shaft means slightly spaced apart 20 along the axial length thereof.

25 4. The device of claim 3 wherein said means for rigidly attaching said wires to said one end of said shaft means comprises a flat on said one end of said shaft means which is bent around and against the middle of said wires.

30 5. The device of claim 3 wherein pairs of said tines are attached to said one end of said shaft means, said pairs of tines having an included angle of approximately 30° therebetween, and said tines being of spring metal 35 wire approximately .0113 inch in diameter and 2½ inches long with .060 inch flocking thereon.,
